CATHODE-RAY TUBE ASSEMBLY

John R. Beers, Briarcliff Manor, N. Y., assignor
to North American Philips Company, Inc.,
Dobbs Ferry, N. Y.

Application April 3, 1944, Serial No. 529,350

5 Claims. (Cl. 250—162)

1

This invention relates to cathode ray tubes, and more particularly to the assembly of certain elements thereof.

It is an object of the present invention to simplify the assembly of elements of a cathode ray tube.

It is another object of this invention to provide an assembly of the type aforesaid wherein elements are aligned automatically.

A further object of the invention is to improve the accuracy and stability of the alignment of elements of a cathode ray tube.

Another object of the invention is to render the assembly of elements of a cathode ray tube more economical.

Other objects, and the manner in which the same are attained, will be apparent from the following description.

Cathode ray tubes usually comprise an electron gun, as a source of a well-defined, focussed beam of electrons or cathode rays, and deflecting means, most commonly in the form of deflecting plates, for controlling or shifting such beam in dependency upon applied voltages. The electron gun usually includes, apart from a cathode and a grid arranged in front thereof, a number of anodes, for example two, which serve as electron-optical lenses for the system and therefore are instrumental in determining the path of the undeflected electron beam, and the deflecting means usually include two pairs of deflecting plates one arranged in front of and at right angles to the other, these sets of deflecting plates being instrumental in determining the path of the deflected electron beam. Evidently, the accurate and stable alignment of the two or several anodes relative to each other, of the two or several sets of deflecting plates relative to each other, and finally, of the anodes relative to the deflecting plates is among the most important requirements in cathode ray tube manufacture; yet, prior to the present invention, this alignment invariably constituted a rather serious, time-consuming and uneconomical operation, moreover yielding results that left much to be desired.

The present invention contemplates simplifying and at the same time, improving the assembly of elements of a cathode ray tube and specifically, insuring the accurate and stable alignment thereof, by providing, in place of the complex rod or similar supporting structure of the prior art, a unitary supporting member, preferably a ceramic sleeve, mounted, for example, on the first anode and mounting in turn, in prearranged spatial relationship, the other elements to be aligned in

2

dividually and collectively, such as a second anode and two sets of deflecting plates. Preferably, this sleeve is cylindrical and slides over the top part of a cylindrical first anode whereafter the second, likewise cylindrical anode having the same outer diameter as the first anode, is inserted in the sleeve to rest in spaced relation to the first anode, openings such as transverse slots being provided in the sleeve for the purpose of welding supply conductors to the anode.

Two sets of longitudinal slots are arranged at right angles to each other in the top part of the sleeve to accommodate and to fix in position both relative to each other and to the anode, two sets of deflecting plates which project from the sleeve sufficiently to have supply conductors welded to their projecting portions. In this manner, the precise and lasting alignment of all elements, individually and collectively, is insured to an extent not heretofore obtained, at a material saving in time and labor.

In the drawing accompanying the present specification and forming part thereof, one embodiment of my invention is shown diagrammatically by way of example.

In the drawing,

Figure 1 shows somewhat diagrammatically a longitudinal section of an electron gun-deflecting plate assembly of a cathode ray tube according to the invention.

Fig. 2 is a transverse section taken along line 2—2 of Fig. 1; while

Fig. 3 is a perspective view of a supporting sleeve according to the invention.

Referring now to the drawing, 1 denotes the cathode and 2 the grid of an electron gun assembly forming part of a cathode ray tube. A sleeve 3 mounted on the grid assembly supports insulating, e. g. ceramic members 4 which, in turn, support a sleeve 5 mounting the first anode 6. This anode is cylindrical and includes a number of disc-shaped insets 7 which have apertures 8 for focusing purposes.

A ceramic sleeve 9, likewise cylindrical and having an inner diameter hardly larger than the outer diameter of the first anode 6, is slid over this anode to be firmly supported thereon, e. g. by resting on sleeve 5, and to be in perfect alignment with the anode 6. The sleeve 9 may be made of Steatite, Isolantite or other suitable refractory material. Two transverse slots 10 are provided on opposite sides of the bottom part of sleeve 9. A supply conductor 11 welded to the anode 6 passes through one of the slots 10 while a lock tab 12 welded to the anode 6, rests in the

other slot 10 to assist in preventing displacement of anode 6 relative to sleeve 9.

A second anode 13 of the same cylindrical configuration and the same outside diameter as the first anode, and provided with disc-shaped insets 14 having apertures 15, is inserted in sleeve 9 above the first anode so as to be positioned in the center portion of sleeve 9. Two transverse slots 16 are provided on opposite sides of the center portion of the sleeve and a supply conductor 17 is passed through one of the slots 16 and welded to the second anode 13, while a lock tab 18 welded to the anode 13 rests in the other slot 10 to assist in preventing displacement of anode 13 relative to sleeve 9.

The bottom and center sections of sleeve 9 are ground to accommodate the cylindrical anodes 6 and 13 while the top section of sleeve 9 is not ground, a step 19 being thus provided between the ground and unground sections which serves 20 as an abutment or stop for the second anode 13.

The top portion of sleeve 9 comprises a set of longitudinal slots 20 arranged above the second anode 13 and accommodating a pair of deflecting plates 21, and another set of similar slots 22 arranged above the slots 20 and at right angles thereto, and accommodating deflecting plates 23. The slots 20 and 22 serve to properly position the plates which may be fastened in the slots in any conventional manner.

In a preferred embodiment of the invention, two mica discs 24 having accurately punched slots 25 to rigidly hold the plates are slipped over the top of the sleeve 9 and anchored in position to assist in the proper alignment and spacing of the plates. Matching eyelets 26 in the mica discs 24 permit them to be rigidly fastened to each other, at the desired spacing, with upright nickel rods or wires 27 which, apart from acting as connectors, also serve as conductors in the welding to the stem leads (not shown in the drawing). Metal or mica snubbers (not shown) based on the mica discs may be provided to support the assembly in the bulb neck of the cathode ray tube.

I wish it to be understood that I do not desire to be limited to the exact details of construction and design shown and described, as various modifications within the scope of the appended claims may suggest themselves to a person skilled in the art.

I claim:

1. In a cathode ray tube, in combination, a cathode and grid assembly, insulating means mounted on said assembly, a first focussing means mounted on said insulating means, a hollow insulating member mounted on said first focussing means, a second focussing means mounted inside said hollow insulating member, at least one pair

4
of slots in said hollow insulating member, and deflecting plates extending through and mounted in proper alignment by said slots.

2. In a cathode ray tube, in combination, a cathode and grid assembly, insulating means mounted on said assembly, a first focussing means mounted on said insulating means, a hollow insulating member mounted on said first focussing means, a second focussing means mounted inside said hollow insulating member, two sets of slots in said hollow insulating member one set arranged above and at right angles to the other, and two pairs of deflecting plates extending through and mounted in proper alignment by said slots.

3. In a cathode ray tube, in combination, a cathode and grid assembly, insulating means mounted on said assembly, a first focussing means mounted on said insulating means, a hollow insulating member mounted on said first focussing means, a second focussing means mounted inside said hollow insulating member, at least one pair of slots in said hollow insulating member, deflecting plates extending through and mounted in proper alignment by said slots, and means surrounding said hollow insulating member and having slots whereby to engage said deflecting plates.

4. In a cathode ray tube, in combination, a cathode and grid assembly, insulating means mounted on said assembly, a first focussing means mounted on said insulating means, a hollow insulating member mounted on said first focussing means, a second focussing means mounted inside said hollow insulating member, at least one pair of slots in said hollow insulating member, deflecting plates extending through and mounted in proper alignment by said slots, and means surrounding said hollow insulating member to hold said deflecting plates in place.

5. In a cathode ray tube, in combination, a cathode and grid assembly, insulating means mounted on said assembly, a first focussing means mounted on said insulating means, a hollow insulating member mounted on said first focussing means, a second focussing means mounted inside said hollow insulating member, two sets of slots in said hollow insulating member one set arranged above and at right angles to the other, two pairs of deflecting plates extending through and mounted in proper alignment by said slots, two annular insulating means having slots whereby to engage and hold in place said deflecting plates, mounted on said hollow insulating member, and means connecting and spacing said annular insulating means.

JOHN R. BEERS.
